UNITED STATES PATENT OFFICE

MAX KAMINETSKY, OF PASSAIC, NEW JERSEY

METHOD OF FORMING METAL LATHS

Application filed February 26, 1929. Serial No. 342,771.

This invention relates to a metal product and in particular to one having expanded portions within its confines which have been expanded without increasing the dimensions of the original sheet.

A particular object of my invention is to provide a metallic sheet in which the cut portions thereof are expanded by ridging or grooving the sheet of material between 10 said cut portions whereby the cut portions are opened up or expanded to permit the use of the material as laths, in building operations, for instance.

A still further object of my invention is 15 to provide a process for the quick and efficient production of the article so that a more substantial and more rigid structure may be obtained and so that subsequent finishing of the material by painting, coating or other- 20 wise, may be eliminated.

While I employ the term "lath" in the specification to follow, in connection with my article, it is to be understood that the use or the process of making it up is not limited 25 by the use of this term. Lath has been one of the biggest items in the expanded metal art and it is an improvement on this metal lath that I have employed my present construction. The lath in use at the present time 30 is flimsy, will cut the hands and clothing of the operator or lather in many instances if not handled carefully, and is not rigid enough to give the plaster or ground mortar coat of a wall the anchorage necessary and 35 is not sufficiently rigid to meet all the necessary requirements of an efficient building unit. Its production has been expensive due to the complicated machinery necessary in 40 expanding it because complicated machinery has been necessary to increase the over-all width of the sheet after the same has been properly slit. In the production of the present lath, soapy water or oil has been used 45 as a lubricant for the cutters and this makes necessary the cleaning of the sheets and drying of them before the black asphaltum or other paint may be applied. Any grooving that may have been done in these expanded sheets was done simply with the idea of trying 50 to make the sheets rigid.

In my improved invention, I have grooved the sheets and have used the grooving for a specific purpose, that of expanding the sheets internally and without increasing their over-all width so that the strength of the material 55 is retained, it is made very rigid by having grooves formed therein and permits the expanded portions to be maintained at the desired width to provide just enough anchor 60 for the brown mortar or cement with which 65 it is coated in the building operation.

In carrying out the steps of my process the material is first subjected to the action of cutters which cut substantially herringbone shaped slits therein at fixed distances apart 65 as the material is intermittently advanced through a suitable machine. The second step in the process is the grooving of the sheet so that the cut portions thereof are slightly 70 expanded and the final step is the complete grooving of the sheets so that final expansion movement of the cut portions is provided to 75 make up the finished article.

To enable others skilled in the art to fully comprehend the underlying features of my invention that they may embody the same in the various modifications in structure and relation contemplated, a drawing depicting a preferred form has been annexed as a part of 80 this disclosure and in such drawings, similar reference characters denote corresponding parts throughout all the views, of which,

Figure 1 is a plan view of a piece of material showing the first step in the operation or after the sheet has passed beneath the cutters 85 to be provided with suitable rows of slits.

Figure 2 is a plan view of the sheet of material illustrated in Figure 1 after it has passed through the second step of the process, namely, the alternate grooving which partly 90 opens the slit portions of the sheet.

Figure 3 is a view of the sheet as illustrated in Figure 2 after it has passed through the final step in the process, that of being grooved alternately to the groove illustrated in Figure 2 whereby the complete expansion of the cut portion is consummated.

Figure 4 is an edge view of the piece of material as illustrated in Figure 3, this view showing how the ribs formed by the slits in 100

the cut portion of the material are slightly bent during the expansion process so that between them they provide a good anchor for the cementitious material placed thereover.

• Figure 5 is a view in side elevation of cutters employed in carrying out a step in the process.

Figure 6 is a view in sectional elevation through the cutter carriers illustrated in Figure 5, this view illustrating how the cutters cooperate to produce the slits in the cut portion of the sheet.

Figure 7 is a view in sectional elevation of parts of crimping rolls employed in my process and illustrating how the grooving or crimping of the sheet of material is performed, and

Figure 8 is a view similar to Figure 7 illustrating the use of three crimping rolls, two of which are riding in the grooves already formed, as illustrated in Figure 7, while the center crimping roll is producing the intermediate groove for the final step in the process of producing the article.

Referring to the drawings in detail, 5 indicates a sheet of metallic material or malleable material which is to be subjected to my process of manufacture. The sheet may be of thin gauge metal and may be used for a number of purposes, a purpose for illustration being that of metal lath as used in the building trade. The sheet of material 5 is passed through a suitable machine and is provided with rows 6 of slits. Adjacent rows of slits being arranged to form a herringbone cut, it being understood that any other shape or angle of cut may be employed to suit the conditions for which the article is manufactured.

These rows of slits are spaced exactly the same distance apart and do not increase nor decrease the over-all width of the sheet. After the sheets 5 have passed under the cutters and each sheet has been provided with the rows of slits 6, it passes under suitable rollers which groove the material as at 7 and between alternate slit portions thereof. This grooving 7, and while the groove is illustrated, it is evident that any suitable crimp may be employed to carry out the same purpose, the slits 6 open up to provide the open portions 8 and the bridge or connecting portions 9 and it will be particularly noted that when this groove 7 has been formed in the sheet, the material is drawn into the groove and the cut portions open up in proportion. The depths of the grooves 7 will determine the amount that the cut portions 6 will open up. After these grooves 7 have been formed, it will be particularly noted that the sheet has not increased in its over-all width or length, substantially.

The next and final step in the process is the grooving of the sheets in the spaces 10 that have heretofore not been grooved, the

previously grooved spaces being indicated by the numeral 11. Suitable grooving rollers are employed which again travel through the pre-formed grooves 7 and in addition to this, intermediate grooving rolls are provided which will groove the sheet as at 12 causing the cut portions to further open out or expand as illustrated in Figure 3.

It is therefore evident that this sheet has been expanded but it has not been expanded in its overall width because even after the final operation has taken place, the sheet of material measures exactly the same in width as it did before it was placed in the machine, or substantially so. The grooving and cutting operations simply causing internal expansion of the cut portions of the sheet to provide what appears to be expanded metal and what really is expanded metal but expanded internally to maintain the rigidity of the sheet as a whole and to provide a unit of manufacture which is rigid and strong.

In view of the fact that I employ two different sets of cutters which are identically the same in construction and operation in order to form alternate cut portions in the sheet of material 5, it is believed that a description of one will suffice. As illustrated in Figures 5 and 6, a cutter shaft 36 carries the cutter holders 37, each of which are made in two portions, a hubbed portion 38 which is secured in any suitable manner as by the spacers 39 at proper intervals along the cutter shaft 36, the cutters 40 being secured against the hubbed members 37 by the collars 41 which are bolted thereto as at 42. Mounting the cutters in this manner makes it very easy to remove them for sharpening and it will be noted that there is a cutter at the diametrically opposite sides of the cutter holders so that every half revolution of the cutter shaft makes one cutting operation by the cutter.

It is to be understood that any number of cutter holders may be employed and the shaft 36 may be of any length depending upon the width of the material to be formed.

It is evident therefore that I have provided not only a process of manufacture involving the idea of expanding a sheet internally so that it overcomes the fault that attends the expanding of a sheet so that its width is increased, but I also use the extra amount of metal that I started with and maintaining the sheet the same width, put the extra material into the ridges or grooves which, being deeper than ordinary, materially strengthen the sheet and adapt it for uses other than for lath and in fact, make it adaptable for many uses where a rigid structure is desired.

In the flat ribs used today on flat, ribbed lath products, they are grooved to the least possible depth necessary, thereby sacrificing rigidity between the studding of a building construction to save metal.

It is evident that my idea not only permits

the deepening of the grooves to make a rigid structure but it also permits the proper expansion of the material internally to provide a suitable anchor for the material to be moulded thereto.

It is evident also that I have provided an article of manufacture in which the first and second grooving after the cutting operation, completes the article and by painting the article first with asphaltum or other suitable paint mixture, sufficient lubricating qualities are imparted thereto to enable its smooth and rapid passage through a machine without breaking the cutters or otherwise hindering their operation. When the sheet emerges after its expansion and cutting, it need not be cleaned or painted because the paint that has completely covered the sheet of material before its passage through the machine, is ample for covering material after it has been expanded in the manner to be described and it will be particularly noted that the expansion takes place within the material, that is, the material is not increased in width but rather the grooving operation successively draws open the cut portions to provide the expansion desired and the depth of the crimp determines the width of expansion of the opening.

Other uses may be made of my improved product such, for instance, as a permanent form or reinforcing in the laying of concrete floors or roofs and in this instance, the expanded sheet can be used over steel joints as a support for a slab of concrete while soft or as a reinforcing for the slab when hard. The gauge of the sheet, would of course, be decided by the engineer or architect according to the requirements and would be made to conform properly to the distances apart or centers of the joists.

At the present time, temporary forms and reinforcing bars are used and by using my new sheet material, the forms can be eliminated and the weight of the steel reinforcing can be substituted in many instances by sheets of a sufficient gauge to give the required weight. As a matter of fact part reinforcing can be used and the balance of the weight can be made up by using sheets of proper thickness.

When in use as a permanent form and reinforce, the sheets would be laid so that the ridges were extending upward and the space between the ridges could, in the expanded portions of the sheet, be filled with a lime and cement and sand moistened putty to form a watertight bottoming for the soft concrete to be spread over the sheet. By the weight of the concrete 4, the putty would be forced somewhat through the expanded portions of the sheet and would form, when dry and hard, rough anchors or keys for the plaster to be used on the ceiling or under side of the hardened concrete.

While I have illustrated and described my invention with some degree of particularity, I realize that in practice various alterations therein may be made, without departing from the spirit of the invention or the scope of the appended claim.

What I claim is:—

The process of producing a sheet of material of the character described which consists in providing a sheet with rows of slits therein, then indenting the sheet with parallel grooves disposed between alternate rows of slits to slightly open the slits and then indenting the ungrooved spaces between the rows of slits with parallel grooves to complete the expansion of the sheet.

In testimony whereof I affix my signature.
MAX KAMINETSKY. [L. s.]
